UNITED STATES PATENT OFFICE.

HIRAM D. AYRES, OF AKRON, OHIO, ASSIGNOR TO THE B. F. GOODRICH COMPANY, OF NEW YORK, N. Y., A CORPORATION OF NEW YORK.

METHOD AND APPARATUS FOR STRETCHING TEXTILE MATERIAL.

Application filed February 9, 1920. Serial No. 357,314.

To all whom it may concern:

Be it known that I, HIRAM D. AYRES, a citizen of the United States, residing at Akron, in the county of Summit and State of Ohio, have invented a certain new and useful Method and Apparatus for Stretching Textile Material, of which the following is a specification.

This invention relates to the treatment of cotton or other fibrous cords or threads, or a parallel set of such cords or threads either in a woven or an unwoven condition, definitely controlled by a stretching operation, preferably exerted continuously on the thread, threads or fabric while the latter is traveling through a fabricating apparatus such as a thread impregnating device or a fabric coating apparatus such for example as a rubber frictioning calender. The object of my invention is, generally speaking, to bring the thread, threads or fabric into a known condition as to its degree of stretchability so as to make it more suitable for certain uses than heretofore, more particularly for such purposes as the building of pneumatic tire casings, balloons and other rubberized or otherwise coated fabric or cord structures.

The invention as herein illustrated and described is embodied and carried out in connection with a calender for applying a coating of plastic rubber to a traveling sheet of fabric, such as ordinary square woven fabric for building rubberized canvas tires, or thread fabric composed of strain-resisting warp threads and occasional weak weft or filler threads for building a known type of so-called cord tires.

To illustrate the application of my invention in the improvement of square-woven fabric, it may be stated that in the ordinary methods of weaving such fabric, the action of the loom in beating up the successive filler threads puts more of a crimp in the warp than in the filler, so that the warp is more stretchable than the filler with a given application of force. The present invention provides a means for "balancing" the fabric by imparting to the warp threads a predetermined degree of stretch corresponding to the amount of their excess of stretchability as compared with the filler threads, and retaining this increased stretch, or all but a small part of it, in the rubberized fabric, by the forcing of plastic rubber

into the interstices of the mesh by means of the frictioning operation.

Of the accompanying drawings, Fig. 1 is a side elevation of a preferred form of my improved fabric stretching apparatus applied to a rubber calender.

Fig. 2 is a plan view thereof.

Fig. 3 is a section on the line 3—3 of Fig. 2.

Figs. 4 and 5 are enlarged sectional views at right angles to each other representing the condition of the unbalanced fabric, and Fig. 6 is a view similar to Fig. 4 showing the condition of the stretched fabric.

In order intelligently to use the apparatus herein provided, on square-woven fabric, it is desirable first to ascertain the amount of excess of stretchability in the warp of the particular length or roll of fabric to be treated, or if thread fabric is being treated, the total stretchability of the warp threads. With square-woven fabric, for example, this may be done by cutting a test-piece from the fabric, loading the warp and filler threads of said test-piece in a definite manner and observing and recording the loadings and the resulting elongations. The test-piece should preferably be in the shape of a Greek cross with arms of equal width, as described in an application, Serial No. 357,315, filed concurrently herewith, the arms of the cross having the transverse threads removed therefrom between the ends of the arms and the central square in order to avoid certain local effects. If this cross-shaped test-piece is then mounted in two sets of grips, a series of known loads applied to its filler threads, for example, the amounts of elongation of said threads observed and successive loads simultaneously applied to the warp threads until their elongations equal those of the filler threads for the known loads, the difference between the respective loadings of the filler and warp will show the amount of excess of crimp in the warp threads and will give an indication of the amount of strain which must be imposed upon the warp of the roll of fabric from which the test-piece was taken in order to stretch it until said excess of crimp is removed.

In the drawings, the broken-line circles 10, 11 and 12 in Fig. 1 represent the upper, middle and lower rolls in one tier of a three-roll calender rotated in the direction of the arrows and adapted to be heated in the

usual manner. 13 is a bank of gum between the two upper rollers which is sheeted over half of the middle roller and then rolled onto the upper side of the fabric 14, the heat of mastication, supplemented generally by steam supplied to the hollow calender rolls, serving to render the rubber sufficiently plastic to cause it to spread properly onto the fabric. 15, 15 are a pair of aligned shaft sections including the usual coupling members on their inner ends for receiving the squared shaft or spindle 16 of the roller 17, which is an intermediate roller adapted to act alternatively as one of the take-up and one of the let-off rollers for the fabric according as one of the other surface of said fabric is being coated. The right-hand one of these shaft sections is connected by suitable gearing at 18, of which a portion is shown in Fig. 2, with the shaft of the lower calender roll 12, and there is the usual friction clutch controlled by a hand wheel between the gear pinion and the shaft section for disconnecting the latter from the power at will, another roller 19 is mounted at the rear of the calender between aligned shaft sections 20, of which one is shown in Fig. 1 connected as usual by gearing (not shown) to the lower calender roll 12 and acts as the final take-up for the fabric when the latter has been coated on both sides, and in that case the front roller 17 acts as the let-off or delivery roller.

On posts 21 in front of the main calender structure are mounted the bearings for a pair of aligned shaft sections 22, having couplings on their inner ends to receive the squared shaft or spindle 23 of a fabric let-off roller 24, said shaft sections carrying a pair of brake-drums 24 of equal size, to which are applied brake-bands 26. The brake-bands have fixed points of attachment 27 at one end to the posts 21, and their other ends are provided with rods 28 pivotally connected with short arms 29 forming part of a rocker responsive to the tension on the fabric, the ends of these rods being screw-threaded and provided with thumb nuts 30 for adjusting the brake-bands. The rocker also includes a fulcrum shaft 31 mounted in bearings on the posts 21 and loosely surrounded by a fabric guide roller 32, together with a pair of upright arms 33 carrying a bearing shaft 34, and a roller 35 loosely journaled on said shaft for guiding the fabric around the upper end of the rocker, this end roller 35 acting as a "feeler" against the under side of the fabric, to and from which the fabric is guided at an angle by the roller 32 and by the roller 35 to be later referred to. Also fixed to the rock-shaft 31 are a pair of arms 36 from which are suspended weights 37 acting on the brake-bands in opposition to the pull of the fabric transmitted through the roller 35 and arms 33. Under one of these weight arms is a cam 38 operated by a handle 39 for holding the brakes out of action when desired, and on the other arm 36 is connected a dash-pot 40 for damping the movements of the rocker.

A mechanism essentially similar to the foregoing is applied to the shaft sections 15 of the intermediate roller 17 on the main calender frame, and is made operative when said roller is delivering fabric through the calender rolls to the rear take-up roller 19, as indicated in Fig. 3. In this mechanism 41, 41 are the brake-drums, 42 the brake-bands with fixed attachments at 43 and their movable ends connected to short arms 44 on a rock-shaft 45. 46, 46 are arms on said rock-shaft connecting by links 47 with arms 48 on a second rocker structure which includes a fulcrum shaft 49 loosely surrounded by a fabric guide roller 50, and a pair of upright arms 51 carrying the bearing shaft for the roller 53, there being also a pair of weighting arms 54 fixed to the ends of the rock-shaft 45 and carrying suspended weights 55. 56 is a dash-pot on one of these weight arms, 57 is a cam and 58 a cam handle under the other arm 54 for disabling the brake-bands 42 at times, such as when the roller 17 is acting as a take-up.

59 is an auxiliary fabric guide roller, adjustable in height, for use when the fabric is given its friction coating on the first side and delivered to the roller 17.

In Figs. 4 and 5, which represent two enlarged sections, at right-angles, of the ordinary square-woven tire fabric as it comes from the loom, it will be observed that the warp threads 60 have a greater amount of crimp or wave in them than the filler threads 61, and in order to balance the fabric so that this excess of crimp shall be removed it is necessary to stretch it lengthwise of the warps so as to bring the fabric approximately to the condition represented in Fig. 6. Assuming that the amount of excess of crimp and consequent amount of excess of stretchability has been determined by testing a sample of the fabric from a particular roll or lot of rolls to be treated as previously set forth, a set of weights 37 and 55 which have been ascertained by trial or calculation as sufficient in amount to impose the necessary degree of stretch upon the fabric to take out this excess of crimp in the warp and restore its balance are then applied to the arms 36 and 54 and the brake-band adjustments such as the nuts 30 are so manipulated that when the cams 38 and 57 are retracted the brakes will be fully applied by these weights. A roller carrying a roll of fabric to be treated is then coupled between the shaft sections 22, the fabric is led around the rollers 32 and 35 in the manner indicated in Fig. 1, over the roller 53, under the roller 59,

around the lower calender roll 12 and onto the take-up roller 17, whose brakes are relieved by means of the cam 57, and whose hand-control clutch is set up to connect it with the gear drive. The draft exerted on the fabric by means of the rollers 12 and 17 and the retardation of the brakes on the shaft section 22 then cause the fabric to be stretched between the let-off and take-up 10 rollers, the amount of tension being maintained substantially constant by the action of the rocker mechanism including the feeler roll 35, whereby the arms 36 are kept floating in an intermediate position. If the retarding effect of the brakes should become so great as to cause this tension to exceed the predetermined amount, the reaction of the increased strain upon the roller 35 will move said roller to the right as viewed in Fig. 1 15 a slight distance and elevate the arms 36 so as partially to release the brake-bands 26, whereupon the feeler roller and connected parts return to their normal position. If the tension should fall below the pre-determined 20 amount, the reverse operation occurs, feeler roll 35 moving slightly to the left and allowing the weights 37 to depress the arms 36, thereby increasing the pull on the brake-bands, increasing the fabric tension and re- 25 storing the feeler roll to its normal position.

When the roll of fabric has been run through and frictioned on one side, it is then fed through the calender with its opposite side uppermost, from roller 17 acting as a let-off, to the final take-up roller 19 (the hand-wheel clutch hereinbefore mentioned being released to disconnect roller 17 from the gearing 18) and is rolled up thereon together with a liner 62 shown in Fig. 3, the course of the fabric being then as indicated by the dot-and-dash line in this view, the automatic tension device for the shaft 16 of the roller 17 being brought into action by retraction of the cam 57 and operating in a manner which will be clearly evident from what has already been described.

The result is or may be a rubberized fabric in a condition of substantial balance as regards the amount of crimp in the warp and filler threads respectively, so that when said fabric is cut in to bias strips and made up into a pneumatic tire, or when it is used in a balloon or other structure, the two sets of threads will be in a condition to do an equal amount of work by reason of being equally stretchable under the same loads. The plastic rubber in the meshes of the fabric serves to hold it stretched in the desired degree, so that when unrolled and fed to the bias cutter, there will be only a very slight contraction of the cut strips lengthwise of the warp. An equivalent effect is obtained when thread fabric is treated, and the tire or other structure into which the fabric is

built is correspondingly benefited by the resulting uniformity in degrees of stretchability or the known relation of degrees thereof in its several plies.

It will be understood that many changes 70 can be made in the particular form of embodiment of my invention.

I claim:

1. The herein described method which comprises ascertaining the elongation of a 75 fibrous thread fabric under a known strain, applying a tension to said fabric bearing a definite relation to said strain to stretch its threads, and fixing said threads substantially in such degree of stretch by other material 80 applied along the threads.

2. The herein-described method which comprises ascertaining the total stretchability of a fibrous thread fabric stretching said fabric by an amount bearing a determinate 85 relation to its total stretchability, and applying to the stretched fabric a plastic substance which preserves the stretch.

3. The herein-described method which comprises ascertaining the total stretchability of a fibrous thread fabric stretching said fabric by an amount bearing a determinate 90 relation to its total stretchability, and applying hot plastic rubber to the stretched 95 fabric.

4. The herein-described method which comprises ascertaining the total stretchability of a flat set of parallel threads, feeding said set of threads longitudinally, progressively stretching said threads by an 100 amount bearing a determinate relation to their total stretchability, and progressively applying to said threads material which holds them in a stretched condition in the form of a fabric.

5. The herein-described method which comprises ascertaining the total stretchability of a flat fabric of parallel fibrous threads, progressively stretching said fabric by an amount bearing a determinate relation 110 to its total stretchability, and frictioning the stretched fabric with plastic rubber.

6. In the treating of woven fabric whose two sets of threads are crimped in different degrees, the method which comprises ascertaining the amount of such difference, imposing upon said fabric, lengthwise of the threads having the greater crimp, a tension which bears a determinate relation to the amount of their excess of crimp, and fixing 120 the fabric in its thus-tensioned condition with a coating of fluent material.

7. In the treating of woven fabric whose warp threads are more stretchable than its filler threads by reason of an excess of crimp 125 in said warp threads, the method which comprises ascertaining the amount of the difference in the stretchability of said threads, stretching said fabric lengthwise of the warp threads in an amount bearing a determinate 130

relation to their excess of stretchability, and frictioning a coat of rubber on the stretched fabric.

8. In the treating of woven fabric whose warp threads are crimped to a greater extent than its filler threads, the method which comprises stretching the fabric lengthwise of its warp until the amount of crimp of the filler threads substantially equals that of the warp threads, and while thus stretched, frictioning a coat of rubber on the fabric.

9. In the treating of woven fabric whose warp threads are crimped to a greater extent than its filler threads, the method which comprises reducing the crimp of the warp threads to a determinate relation to that of the filler threads by continuously, progressively and uniformly stretching a length of said fabric longitudinally thereof, and frictioning it with rubber, while said fabric is being fed longitudinally.

10. In the treatment of woven fabric whose warp threads are crimped more than its filler threads, the method which comprises determining the approximate amount of the excess of stretchability in the warp of the fabric to be treated, progressively imposing upon said fabric, lengthwise of its warp, a substantially constant tension adapted to remove said excess, and progressively applying to the tensioned fabric a plastic coating.

11. In a fabric-stretching machine, the combination of a roller calendering appara-

tus having means for propelling a sheet of fabric and applying a plastic coating thereto, a let-off roller for supplying the fabric, a brake for said roller, and means responsive to the tension on the fabric for controlling said brake.

12. In a fabric-stretching machine, the combination of a calender having means for applying a plastic coating to one side of a sheet of fabric, and two devices associated therewith and responsive to the tension on said fabric for regulating the amount of such tension, said devices being operative alternately according as one or the other surface of the fabric is being coated.

13. In a fabric-stretching machine, the combination of a calendering apparatus having a tier of three calender rolls for propelling a sheet of fabric and applying plastic gum thereto, a fabric let-off roller having a brake, means responsive to the tension on the fabric leaving said roller for controlling said brake, a final fabric take-up roller, an intermediate roller adapted to act alternately as a take-up and let-off roller, a brake for said intermediate roller, means responsive to the tension on the fabric leaving said intermediate roller for controlling its said brake, and devices for disabling said brakes.

In witness whereof I have hereunto set my hand this 5th day of February, 1920.

HIRAM D. AYRES.
